UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed June 4, 1924. Serial No. 717,701.

This invention relates to typewriting machines, especially to ribbon vibrating, guiding and guarding devices as used in connection therewith, and more particularly to 5 means for preventing the ribbon from fouling with the type-bar guide of an Underwood portable typewriter.

Ordinarily, when raising the platen, the lower edge of the ribbon is carried high 10 above the type-bar guide, and when the ribbon is lowered to its normal position there is a possibility for it to catch on the type-guide. This is apt to happen when operating rapidly, especially when the platen is 15 lowered before the operator releases the type-key.

It is therefore a feature of the invention to provide a combined ribbon vibrator and shield which will effectively avoid such occurrences, and the device is made extremely 20 light to avoid overthrow of the ribbon, due to acquired momentum in its rapid movement, and also to reduce effort on the part of the operator.

25 It is a further object to provide a combined ribbon vibrator and shield that can be made from a single piece of sheet-metal in an economical manner, and which can be substituted for corresponding existing portions of a typewriting mechanism without material change in the same.

30 Other features and advantages will hereinafter appear.

In the accompanying drawings,

35 Figure 1 is a partial front elevational view of an Underwood portable typewriting machine with the platen in lower-case position and the ribbon in normal position below the printing line, parts being broken away to 40 show the structure, the view also showing the application of an embodiment of the invention.

45 Figure 2 is a transverse sectional view of the same taken in a plane substantially on the line 2—2 of Figure 1.

50 Figure 3 is a view similar to Figure 1, but showing the platen in lower-case position and the ribbon positioned to print on the lower field.

55 Figure 4 is a view like Figure 3, but showing the type-guide in its lowered position and the ribbon still raised.

60 Figure 5 is a perspective view in detail of the combined ribbon vibrator and shield.

Referring more in detail to the drawings, 55 the numeral 10 designates a fragmentary portion of a type-bar as used with a typewriting machine, the same striking upon a platen 11, mounted on a shaft 12, which is journaled in the platen-frame end plates 13, 60 these plates being connected by cross bars 14 and 15 respectively at the front and rear, and supported on carriage rails 16 and 17, between which bars and rails are interposed anti-friction elements, as the balls 18 and 65 rollers 19, thus permitting the platen-frame to be moved easily lengthwise of a carriage support, generally designated by the numeral 20, this carriage support being shiftable into different horizontal planes by the usual 70 mechanism (not shown) and which forms no part of the present invention.

Carried by the typewriter machine frame at the front is the usual slotted segment bar 21, and secured to it by screws 22 is a rigid type-guide 23 having upwardly-extending fingers 24 providing between them a guide slot 25 for engagement with a shoulder 10^a of the type-bar. The type-guide 23 has an opening 26 through which the graduations and numerals on the usual scale 27 can be readily seen, and the lower edge of the opening 26 is raised at its center, providing an index pointer 28 in register with the printing position designated in Figures 1, 3 and 85 4 by the character "X".

A ribbon-vibrating mechanism, generally designated by the numeral 30, includes a plate 31 fastened to the rail 16, on which the platen-frame moves, by screws 32, and extending from the upper edge of the plate are two parallel spaced uprights 33 equi-distant from the printing point X. The central lapped portion of the plate 31 contains an elongated vertical slot 34 in which operates 90 a headed stud 35, engaged in the vibrator as hereafter explained, and gib elements 36, formed on the upper edge of the plate 31, engage with the front cross bar 14 of the platen-frame assisting in maintaining it on the rail 16. An inwardly-projecting lever arm 37 of the vibrator actuating mechanism (not shown) is operatively connected to the headed stud 35 and when in operation moves the lever arm 37 upwardly to bring the usual ribbon 38 to the printing point, the ribbon being fed lengthwise between spools (not shown) in the ordinary manner. 100 105

The actuating mechanisms for the ribbon-vibrator, spools and feed arrangement for the ribbon, together with the case-shifting means for the platen, form no part of the present invention, but are described in the patent to George W. Campbell, No. 1,370,281, dated March 1, 1921.

In operating typewriting machines having similar features and arrangement of parts to those described, at a high rate of speed, the platen, if shifted from a higher to a lower case position in improper sequence, that is, before the type-bar is released, may cause the ribbon to engage the type. Such condition is conducive in causing a portion of the ribbon, between its supporting arms and over the fingers of the type-guide, to become slack and its edge to curl when the type-bar and ribbon-vibrator return to their normal position. Such slack in the ribbon has a tendency during the lowering thereof to catch on the type-guide fingers and cause annoyance to an operator.

The purpose of the present invention is largely to provide a combined ribbon vibrator and shield which positively prevents interference between the ribbon and type-guide. This device is indicated generally by the numeral 40 and shown in detail in Figure 5 of the drawings, where it may be seen to be comprised of a single piece of sheet metal shaped to present a pair of opposed, outwardly-curved arms 41, having at their juncture a pendant lug 42 containing a perforation 43 engageable with the stud 35.

The upper, inner edge portions of the arms 41 are provided with outstanding integral clips 44 to slidably engage with the upright elements 33 of the vibrator support plate 31. At the upper extremities of the arms 41 are diverging loop members or eyes 45, the front bar 46 of which contains an opening 47 to permit entrance of the ribbon, these loops being bent angularly forward and smoothly finished to avoid damaging the ribbon, which is passed from one loop to the other across the rear of the plate.

Extending inwardly from the arms 41, in a plane substantially equivalent to the center of the loops 45, are inreaching elements or projections 48 terminating in vertical parallel spaced shields or horns 49 equivalent in length to the width of the ribbon, and having between them an open space 50 through which the type pass in striking upon the ribbon 38 disposed in front of the platen 11.

From the foregoing it will be seen that whenever the vibrator-actuating mechanism is operated, the combined vibrator and shield will be raised, together with the ribbon, presenting the ribbon to the printing point and thereafter lowered upon release of the key-lever. It is to be noted that the lower portions of the shield elements 49 extend at all

times below the lower edge of the ribbon thereby effectually preventing the ribbon from making contact with the type-guide, irrespective of their relative positions or movement transmitted to the vibrator.

Variations may be resorted to within the scope of the invention, and portions of the improvements may be used without others.

Having thus described my invention, I claim:

1. In a typewriting machine, the combination with a type-guide, of a ribbon-vibrator having a substantially U-shaped body including upwardly-directed arms, ribbon-receiving eyes extending outward adjacent the ends of said arms, inreaching elements projecting toward the printing point and overlying the ribbon, whereby to maintain the ribbon in flat condition, and downwardly-projecting horns carried upon the ends of said elements and preventing the ribbon from fouling on said type-guide.

2. In a typewriting machine, the combination with a type-guide, of a ribbon-vibrator having a substantially U-shaped body including upwardly-directed arms, ribbon-receiving eyes extending outward adjacent the ends of said arms, inreaching elements projecting toward the printing point and overlying the ribbon, whereby to maintain the ribbon in flat condition, and downwardly-projecting horns carried upon the ends of said elements for preventing the ribbon from fouling on said type-guide, the horns extending slightly below the bottom edge of the ribbon.

3. In a typewriting machine, the combination with a type-guide, of a ribbon-vibrator having a substantially U-shaped body including upwardly-directed arms, ribbon-receiving eyes extending outward adjacent the ends of said arms, inreaching elements projecting toward the printing point and overlying the ribbon, whereby to maintain the ribbon in flat condition, and horns carried upon the ends of said elements for preventing the ribbon from fouling on said type-guide, the horns extending slightly below the bottom edge of the ribbon, and also having portions extending upwardly adjacent the top edge of the ribbon.

4. In a typewriting machine, the combination with a type-guide, of a ribbon-vibrator having a substantially U-shaped body including upwardly-directed arms, a ribbon-receiving eye adjacent the end of each arm, the eyes being disposed angularly outward in opposite directions from the sides of the arms and directed toward the front, inreaching elements projecting toward the printing point and overlying the mid-section of the ribbon, and horns carried by the ends of said elements, the horns having portions extending downward and terminating at points below the bottom edge of the ribbon,

said horns also having portions extending upward to points adjacent the top edge of said ribbon.

5. A ribbon-vibrator for a typewriting machine having a body including a pair of upwardly-extending arms, eyes carried by said arms for receiving and guiding a ribbon, ribbon-shielding elements extending inwardly toward one another from the arms, 10 and horns carried by the ends of said elements and including ribbon-shielding portions extending both above and below said elements, the ribbon-guiding eyes being so disposed relatively to said horns that the 15 lower portions of the latter extend below the bottom edge of the ribbon, while the upper portions of said horns extend to points adjacent the top edge of the ribbon.

6. In a typewriting machine, the combination with a type-guide secured to a fixed part of the machine, of a vibrator arranged to receive a ribbon and to oscillate the same into different horizontal planes adjacent the type-guide, said vibrator including widely spaced loops for supporting the ribbon, and inreaching ribbon-shielding elements carrying vertically-disposed horns terminating below the lower edge of the ribbon at each side of the printing point, the horns being effective to prevent the ribbon from fouling on 25 said type-guide, the shielding elements guid-

ing the ribbon in flat condition between said widely spaced loops.

7. In a typewriting machine, the combination with a type-guide secured to a fixed part 35 of the machine, of a vibrator arranged to receive a ribbon and to oscillate the same into different horizontal planes adjacent the type-guide, said vibrator including widely spaced loops for supporting the ribbon, inreaching ribbon-shielding elements carrying 40 vertically-disposed horns, the lower ends thereof terminating below the bottom edge of the ribbon at each side of the printing point, the horns also including portions extending upward to points adjacent the top 45 of the ribbon.

8. In a typewriting machine, the combination with a type-guide, of a ribbon-vibrator including a pair of widely spaced divergent 50 arms having loops at their ends for reception of a ribbon, and ribbon-shielding members extending inwardly of said loops, interja- 55 cent the ribbon and type-guide, to maintain the wide stretch of ribbon in flat condition, said members also carrying vertically-ar- ranged horns disposed on opposite sides of the printing point and terminating below the bottom edge of the ribbon, said horns preventing the ribbon from fouling on said 60 type-guide.

JOHN WALDHEIM.
